UNITED STATES PATENT OFFICE.

CHARLES J. VAN DEPOELE, OF CHICAGO, ILLINOIS.

ELECTRIC-CABLE CONVEYANCE.

SPECIFICATION forming part of Letters Patent No. 329,104, dated October 27, 1885.

Application filed June 29, 1885. Serial No. 170,112. (No model.)

To all whom it may concern:

Be it known that I, CHARLES J. VAN DEPOELE, a citizen of the United States of America, residing at Chicago, in the county of Cook and State of Illinois, have invented certain new and useful Improvements in Electric-Cable Conveyances, of which the following is a specification, reference being had therein to the accompanying drawings, in which—

- 10 Fig. 1 shows a side elevation of the way; Fig. 2, an end view of a car in position, with one end removed; Fig. 3, a detail in side elevation showing the arrangement of the gearing, driving-chains, &c.; Fig. 4, a side elevation of a covered cable with a car in position, but with the sprocket-wheels and chain shown in the preceding figure removed. Fig. 5 shows, on a larger scale, a section of the cable and negative conductor with the support for the latter in position. Fig. 6 shows a side view of a support for the cable to be used in rocky or other suitable localities. Fig. 7 shows a plan of a short section of the covered cable shown in Fig. 4. Fig. 8 shows a side view of some of the sections of the cable-covering. Fig. 9 is a modification of the same. Fig. 10 is a cross-section of the cable and its covering. Fig. 11 is an edge view of one of the pulleys O, in Fig. 4. Figs. 12 and 13 are sectional details of different forms of the cable-holders shown in Fig. 4. Fig. 14 is an end view of one of the sections of the cable-covering provided with ears to receive the link for supporting the negative conductor. Fig. 15 shows two vertical sections of one of the cable-supporting wheels, taken at right angles to each other.

My invention relates to a system of cable-ways intended more particularly for that class in which electricity forms the motive power, although it may be used with other means of propulsion.

The invention consists in the peculiar combinations and the construction and arrangement of parts hereinafter described and claimed.

Referring to the details of the drawings, A represent a series of posts, each of which is supplied with a bracket, B, of any suitable form, but preferably like that shown in Fig. 2, and having a cap, b, which fits on the top of the post, and a semicircular curved portion, b', to embrace the post at a lower point, which

may be bolted thereto, if preferred. From the center of this bracket runs a cylindrical bar, C, preferably cast in said bracket, which forms an axle for a grooved wheel, D. In the groove of this wheel lies the supporting-cable E, which is preferably an electrical conductor also, and in order that it may the better serve this purpose I prefer to make the interior strands, e, of copper, in order that the cable may be a better conductor, and the exterior strands, e', of steel, in order that it may be sufficiently strong to withstand the strain and durable enough to withstand the wear to which it will be subjected. Below this cable I suspend a conducting-wire, F, for the return-current, preferably in the following manner: Below the cable E, I attach in any convenient manner, as by soldering or otherwise, a series of clips or hangers, G, each of which partially embraces the under side of the cable, and is provided with a groove, g, in which a link, H, is hung by means of a pin passing through the clip and link. This link carries an insulator, I, and from this insulator hangs another link, J, secured to another clip, G', similar to hangers G, but rather smaller, which is fastened to the negative conductor F. By this means the cable or positive conductor carries the negative conductor, and yet is perfectly insulated from it. Suspended from the cable is a car, K, of any convenient size, but it should be of such dimensions as to have a compartment for the motor and intermediate connections and a compartment for the material to be carried. This car is preferably suspended by a lever, L, and a series of links, M N, carrying pulleys O, which are firmly attached to shafts P, running in bearings in the top of the links M. Each of these shafts carries a sprocket-wheel, Q, on which and on another sprocket-wheel, R, runs a flat drive-chain, S. The wheel R is keyed fast on a shaft, I, that carries a gear, U, which meshes with a pinion, V, of an electric motor, W, or any other suitable driving mechanism.

The arrangement of the levers and links above referred to will be found to be the preferable arrangement where the way is arranged to run from a higher to a lower level, or the reverse; but where the way is comparatively level the lever L will be found unnecessary, as in that case each of the links M may be provided with

a flange at its lower end, by which it may be fixedly connected to the car, as shown in dotted lines in Fig. 2.

For ordinarily level ways, or where only slight inclines are found, a plain cable can be used to considerable advantage; but where there is a very steep incline the construction of cable shown in Figs. 4 and 7 will be preferable. In this case the cable E will be covered with a series of malleable castings, which I denominate "steps." These are represented at XX, and, as will be seen on the detail Fig. 7, each consists of a short tube fitting closely around the cable and provided with lugs or cogs x on each side, for a purpose hereinafter referred to. One end of each of these steps is provided with tongues or projections x', while the other end has notches x² of corresponding size, so that when a series of them are set on a cable they are incapable of turning independently.

Instead of making the steps with tongues and notches, as shown in Fig. 8, they may be "halved" one into the other, as shown in Fig. 9, and by making the longitudinal edges of the joints inclined, as shown in said figure, they will become tightened upon the cable as they are driven together. For the sake of lightness and economy of material I propose to make them open at top and bottom, as shown at x² in Fig. 7, although this is not essential. Besides the use of these steps for ascending inclines, it will be seen that they will prevent the wear on the cable itself, as all the wear will come on the steps, and thus the cable may last indefinitely, at least so far as wear from the pulleys O is concerned, because the steps can be removed should they become badly worn, and thus the wearing-surface of the cables can be renewed as often as required. At the beginning and end of each incline will be placed a holder, (shown at YY') through which the cable passes, and which is provided on each side with lugs x at distances apart corresponding to the lugs x on the steps XX. These holders are made in two pieces, which may either be made in the form shown in section in Fig. 12 or 13, in one of which, Fig. 12, one of the parts is made hook-shaped, and the other section is formed to fill in the circle, and having an extension downward, by which it is fastened to the larger piece by means of bolts passing through both. The other form is made as shown in cross-section in Fig. 13. In both cases the holder is preferably secured to an arm corresponding to the arm C, projecting from a post similar to A, on which arm it is secured by means of a nut, which also serves the purpose of securing the two parts together. One end of the holder is provided with a tongue and the other with a notch corresponding to the tongue and notch on the steps, the object of which is to prevent the steps on the cable from turning. When these steps are used, instead of soldering the clips G to the positive cable E, I have ears cast on the bottom of some of the steps, in

which is secured one of the rods H, for carrying the negative conductor F. With this form of cable I propose to use pulleys like that shown in side view at O in Fig. 4 and edgewise in Fig. 11, having a central groove, e, adapted to fit an ordinary cable like that shown in Figs. 1 and 2, and teeth o' on each side adapted to pass between the cogs on the steps, as shown in Fig. 4.

In some cases, in lieu of using posts to support the wheels D or holders Y, I propose to use the device shown in Fig. 6, where the locality is suitable, such as the side of hills or mountains. In this case 1 represents a round iron bar, which is driven and wedged into a hole drilled into the side of a rock, and which may be stayed in any convenient manner, but preferably by means of a brace, 2, having the lower half of a box, 3, cast on its top, which is provided with a cap, 4, securely bolted to it, which clamps the bar and brace 1 and 2 fast together. On this is secured one of the supporting-wheels D in any convenient manner.

The wheels D may be made in any known manner; but I prefer to make them with a central hub, 7, to receive the supporting-bar, and with side flanges, 8, of thin Bessemer steel, between which are clamped segments of wood, 9, with the grain radiating from the center, so that the wear comes on the end of the grain.

To connect the negative conductor F with the motor, I prefer to use a pulley, 5, grooved to approximately correspond inversely with the bottom of the conductor, which pulley is set in a spring-bearing, 6, which may be of any approved form, and which bearing is in electrical connection with the negative pole of the motor.

The course of the current is as follows: The current passes from the positive or supporting cable through the pulleys O, shaft P, links M, lever L, and shaft I, by any suitable conductor, to the positive brush of the motor, through the motor, and from it to the negative conductor F, through the bearing 6 and pulley 5, as above described.

I do not limit myself to the exact construction above set forth; as it is evident that it may be varied without departing from the spirit of my invention. For instance, where the cable is designed to be used in a comparatively level country the lever L may be dispensed with by firmly attaching the lower end of the links to the car, as shown by dotted lines in Fig. 2.

By the construction here shown, as is evident, a very convenient system of conveyance is provided, which will be found particularly advantageous in mining or mountainous countries, or where the surface of the ground is much broken or uneven.

It is evident that the plain uncovered cable may be used on the level portions of the line, and that the covering or steps need only be used at such points where the incline is very great, as the wheel shown in Fig. 11 will run

and propel the car equally well, whether on the uncovered level cable or on the inclined step-covered cable.

I have shown the highest part of the inclined cable supported on a post; but it is evident that in most cases it will be most convenient to use a device like that shown in Fig. 6.

I am aware that iron wires or rods have been used to support a copper conductor hung below it for telegraphing purposes by means of wires surrounding both the iron wires or rods and the copper conductor; but such arrangement could not be used for the passage of a car, as the hanging devices would prove serious obstructions to the passage of the car and the wheel or brush used for making the connections. I am also aware that it has been proposed to carry a cable on supports, from which supports hangs a conductor for the return-current, and I make no claim to either construction, as I consider them essentially different from mine, one of the main features of which is a supporting-cable provided with hangers firmly fastened at suitable intervals to the under side only of said cable, so as to form a suitable support for the insulating-carriers for the lower conductor, and yet leave the upper part of said cable free for the passage of the car-wheels.

Some of the features herein shown and described are not claimed herein, but form the subject-matter of another application filed July 31, 1885, and numbered 173,190.

35 What I claim as new is—

1. In a system of electrical-cable conveyance, a cable provided with hangers firmly fixed to the underside of the same for the support of the lower conductor, substantially as described.

2. In a system of electrical-cable conveyance, a supporting-cable and an electrical conductor, the supporting-cable having hangers, as G, to support the conductor, said hangers having a concave upper surface to fit the under side of said cable and hanging from the same, whereby the upper cable is left free for the travel of the cars, substantially as described.

3. In a system of electrical-cable conveyance, a supporting-cable, a conductor below the same, and insulating-carriers between them secured to the bottom of the supporting-cable and the top of the conductor, substantially as described.

4. In a system of electrical-cable conveyance, two conductors, one of which carries the other by an insulating-support, the upper conductor having a hanger, as G, fastened to its bottom only and the lower conductor having a clip, G', attached to the top thereof only, whereby the top of one conductor and the bottom of the other are left clear, substantially as described.

5. In a system of electric-cable conveyance, two conductors, one of which carries the other, hanging device between the two having

one part of the same in metallic connection with the upper cable, another part in metallic connection with the lower cable, and an insulating part between the two metallic connections, substantially as described.

6. In a system of electric-cable conveyance, a positive conductor, E, a link, H, connected thereto, an insulator, I, connected to said link, and a second link, J, connecting the insulator with the negative conductor, substantially as described.

7. In a system of electric-cable conveyance, and in combination with the links connecting the lower conductors with its main support, a bell-shaped insulator, as I, provided with apertures to receive said links, one above the bell and the other below the same, substantially as and for the purpose specified.

8. In a system of electric-cable conveyance, a support, an arm, as C, extending horizontally therefrom, a groove-pulley mounted on said arm, a conducting-cable resting on the groove of said pulley, and a conductor suspended below the same, substantially as described.

9. In a system of electric-cable conveyance, a support, as A, having a horizontal axle, a grooved pulley mounted thereon, a main conducting-cable resting in the groove, and a return-conductor below the same, in combination with a car suspended from the main cable and a motor carried by the same, and electrical connections, substantially as described, between the motor and the two conductors, whereby the current operates the motor and the latter drives the car, substantially as described.

10. In a system of electric-cable conveyance, a supporting and conducting cable, a return-conductor, a lever, L, links M M and N, pulleys O, shafts P, wheels Q, a motor, as W, and mechanism, substantially as described, between the motor and the wheels Q for driving the car, as set forth.

11. In a system of electric cable conveyance in which a conductor is suspended below a supporting-cable, a sectional covering for a cable, the sections of which at suitable distances apart are provided with ears to receive supports for the lower conductor, substantially as described.

12. In a system of electric-cable conveyance, a conducting and supporting cable provided with an outer covering of strong wires to sustain the load, and a center of better conductivity to carry the current, both being electrically connected, and a conductor for the return-current suspended below said cable, substantially as described.

In testimony whereof I affix my signature in presence of two witnesses this 27th day of June, 1885.

CHARLES J. VAN DEPOELE.
